SAFETY BUCKLE

Filed May 8, 1929

BY

Robert H. Young
ATTORNEY

UNITED STATES PATENT OFFICE

ALBERT C. FOULK, OF DAYTON, OHIO

SAFETY BUCKLE

Application filed May 8, 1929. Serial No. 361,427.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates generally to improvements in buckles and more particularly to a device of that general character which is especially designed and adapted for use in connection with belts of the type worn by aviators, firemen, window cleaners and other persons engaged in more or less hazardous undertakings.

An object of this invention is the provision of a buckle for belts which is extremely strong in its general make-up and in its resistance to any opening action produced by the usual pull thereon.

The invention is further characterized by the provision of a buckle which will not readily become disengaged accidentally while in use because of slack in the belt of the user or thru contact of the body with different articles.

A further object of the invention is the provision of a buckle which requires no particular skill in handling and having a positive locking catch incorporated thereon so arranged as to permit of its being quickly released should occasion require it.

A still further object of the invention is the provision of a buckle having a double independently operated latching mechanism so arranged as to make it practically impossible for the buckle to be opened by an accidental blow imparted from any direction and yet permit of its being rapidly opened when desired.

The invention consists in the details of construction and in the combination and arrangement of the several parts whereby certain important advantages are attained and mainly comprises two separable members together with means for effectively holding the same against separation when in locking relation, all of which is hereinafter more particularly described and definitely pointed out in the claims.

In the accompanying drawings Fig. 1 is a perspective view of a safety belt secured to a

seat and provided with a buckle embodying my invention.

Fig. 2 is an enlarged plan view of the buckle shown in locked position.

Fig. 3 is a view similar to Fig. 2 showing the parts arranged in a full open position.

Fig. 4 is a side elevation.

Fig. 5 is a section taken on line 5—5 of Fig. 2.

Fig. 6 is a section taken on line 6—6 of Fig. 2.

Fig. 7 is a fractional detail view showing the locked position of the releasing members in full line and the unlocked position thereof in dotted lines.

Corresponding parts are designated by corresponding numerals throughout the drawings.

As disclosed in the drawings, the buckle comprises essentially two separable members 10 and 11, each adapted to have an end portion suitably secured to a strap or other flexible member 12 of any desired kind, in this particular instance a safety belt of the type used by aviators being illustrated. In providing a belt for persons of this character, the belt of course must be sufficiently strong to stand the weight of a person, and the catch or buckle holding the ends together should be strong enough to support at least the weight of the person using the belt, and also must be capable of quick disengagement in case of an emergency.

To this end the member 11 hereinafter to be referred to as the base member is provided with a connecting piece 13, one end of the said flexible member 12 being adapted to extend around the said connecting piece and sewed or otherwise suitably secured, as shown in Fig. 2.

The member 10 comprising a link fitting is adapted to be engaged by the hook ends 14 and 15 of a clamping member 16 hinged to the base member at points 17 and 18. When folded over into locked position the member 10 is held in position between socket forming lugs 19 and 20 provided on base member 11 and the lugs 14 and 15 on the clamping member 16. The hook ends are connected by an operating bar 21 having a flat portion 22

which provides a hand hold, to permit of the parts being quickly moved from the full closed position shown in Fig. 2 to the full open position shown in Fig. 4.

5 Mounted on the clamping member 16 are latch pieces 23 and 24 of substantially similar design which comprise, essentially, levers 25 and 26 having shafts 27 and 28 adapted to bear in suitable bearing portions 29 provided in the clamping member. Coiled springs 30 are shown mounted on shafts 27 and 28 respectively which are adapted to rotate the latch piece into a flush position, as shown in dotted line in Fig. 6, when the buckle is in a released position. In this way, 10 the link fitting 10 is free to slide off the clamping member 16.

15 The latch pieces 23 and 24 have cam portions 31 formed integrally thereon which are engaged by projecting hooks 32 provided on the base member.

20 When it is intended to close the buckle, the link fitting 10 is first placed in the position shown in Figs. 3 and 4, the hinged member being moved on its pivots to the position 25 shown in Fig. 2. At this time latch pieces are engaged by the projecting hooks 32 and assume the position shown in full line in Fig. 7, thus effectively locking the buckle. When it is 30 intended to open the buckle, the levers 25 and 26 are grasped manually and simultaneously squeezed inwardly, assuming the position shown in dotted lines in Fig. 7. A slight upward pull moves the latch pieces 23 and 24 clear of the projecting hooks; the levers 25 and 26 are released, and immediately assume a flush position relative to the clamping member 16. At this time the buckle is in a released position. Any additional pull on 35 the belt ends causes the clamping member to pivot on its bearing portions 14 and 15 and permits the link fitting to slide off its end. By means of this double independent latch system it is practically impossible for the buckle to be opened, inasmuch as it is necessary to give a simultaneous and opposite pull to the latches in order to release them.

40 From the foregoing description, it is thought to be obvious that a buckle constructed in accordance with my invention is particularly well adapted for use by aviators by reason of the convenience and facility with which it may be assembled and safely operated and it will also be obvious that my 45 invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

50 1. A buckle for belts, comprising a base member adapted to accommodate one end of

said belt, a link fitting connected to the other end of said belt, a readily releasable clamping member having means co-operating with means on said base member and with said link fitting for interlocking said link fitting 70 with said base member, said clamping member being provided with a permanently attached latch movable therewith and relative thereto and said base member being provided with cooperating holding means to engage 75 said latch for releasably and positively locking said clamping member to said base member.

2. A buckle for belts comprising a base member adapted to accommodate one end of 80 said belt, a link fitting connected to the other end of said belt, guiding lugs mounted on said base member adjacent each side thereof providing link receiving sockets, said lugs being adapted to receive one end of said link 85 fitting when the buckle is in a closed position, a clamping member pivotally mounted on said base member adjacent to the free end thereof, said clamping member having a pair of spaced hook shaped ends positioned adjacent the pivots thereof, and means on said 90 clamping member and base member positively locking the clamping member to said base member when in a closed position.

3. A buckle for belts comprising a base 95 member adapted to accommodate one end of said belt, a link fitting connected to the other end of said belt, co-operating holding means on said base member, a readily releasable 100 clamping member pivoted to said base member and having means cooperating with means on said base member and with said link fitting for interlocking said link fitting with said base member, and means permanently attached to said clamping member 105 adjacent to its free end adapted to interlocking engage said co-operating holding means on said base member when said clamping member is in a closed position.

4. A buckle for belts comprising a base 110 member adapted to receive one end of said belt, said member having spaced end posts mounted thereon, a link fitting connected to the other end of said belt, a pair of spaced 115 projecting hooks mounted on said base member, a substantially U shaped clamping member pivotally mounted on said end posts and having means cooperating with means on said base member and with said link fitting for interlocking said link fitting with said base member, and means adjacent the closed end of said U shaped clamping member adapted to latchingly engage the said projecting hooks on said base member when said clamping member is in a closed position.

5. A buckle of the class described comprising a belt holding base member, a link fitting, a clamping member pivotally mounted on said base member and having means thereon cooperating with means on said base member.

and with said link fitting for interlocking said link fitting with said base member, co-operating holding means on said base member, and yielding means mounted on said 5 clamping member for latchingly engaging said co-operating holding means when said clamping member is moved into closed position.

6. A buckle of the class described comprising a belt holding base member, a belt fastening link fitting, a releasable clamping member pivotally mounted on said base member having means thereon cooperating with means on said base member and with said 10 link fitting for interlocking said link fitting with said base member for detachably securing said link fitting to said base member, co-operating holding means on the base member, and a yieldingly urged latching device 15 mounted on said clamping member adapted to engage said co-operating holding means when said clamping member is moved into closed position to positively lock said clamping member to said base member.

25 7. A buckle of the class described comprising a belt holding base member, a belt fastening link fitting, a clamping member pivotally mounted on said base member having means thereon cooperating with means on 30 said base member and with said link fitting for interlocking said link fitting with said base member for detachably engaging said link fitting and said base member, co-operating holding means on said base member, and a 35 latching device comprising a pair of spaced levers journaled in said clamping member and having portions thereon adapted to interlockingly engage with said co-operating holding means whereby to lock said clamping member to said base member when the buckle 40 is in a closed position.

8. A buckle of the class described comprising a belt holding base member, a belt fastening link fitting, a clamping member pivotally mounted on said base member having means thereon cooperating with means on 45 said base member and with said link fitting for interlocking said link fitting with said base member for detachably engaging said link fitting and said base member, and a manually detachable latching device comprising a pair of spaced manually operated levers journaled in said clamping member and having cam faced portions thereon adapted to 50 interlock with co-operating holding means on the base member whereby to lock said clamping member to said base member when in a closed position.

55 9. The combination with a separable buckle comprising a belt holding base member having a clamping member pivotally mounted thereon and a belt fastening link fitting, said clamping member having means thereon cooperating with means on said base member and with said link fitting for interlocking

said link fitting with said base member, of means comprising a pivoted latch member mounted on said clamping member adapted to interlockingly engage co-operating holding means on said base member when said clamping member is moved into closed position. 70

10. The combination with a separable buckle comprising a belt holding base member having a clamping member pivotally mounted thereon and a belt fastening link fitting, said clamping member having means thereon cooperating with means on said base member and with said link fitting for interlocking said link fitting with said base member, of a latching device pivotally and yieldingly mounted on said clamping member and holding means on said base member adapted to lockingly engage said latching device when said clamping member is moved into closed 80 position. 85

11. The combination with a separable buckle comprising a belt holding base member having a clamping member pivotally mounted thereon and a belt fastening link fitting, said clamping member having means thereon cooperating with means on said base member and with said link fitting for interlocking said link fitting with said base member, of a latching device therefor comprising a pair of spaced levers journaled in said clamping member, and a pair of similarly spaced projecting hooks provided on said base member whereby to latchingly engage said levers when said clamping member is 90 moved into a closed position relative to said base member. 95

12. The combination with a separable buckle comprising a belt holding base member having a clamping member pivotally mounted thereon and a belt fastening link fitting, said clamping member having means thereon cooperating with means on said base member and with said link fitting for interlocking said link fitting with said base member, of a manually releasable latching device therefor comprising a pair of spring actuated latching levers journaled in said clamping member, and a pair of rigid projecting hooks provided on said base member adapted to be 100 detachably engaged by said latching levers when the buckle is in a closed position. 110

13. The combination with a separable buckle comprising a belt holding base member having a clamping member pivotally mounted thereon and a belt fastening link fitting, said clamping member having means thereon cooperating with means on said base member and with said link fitting for interlocking said link fitting with said base member, of a locking device therefor comprising a pair of independently operated members having spaced and parallel aligned shafts journaled in said clamping member, said shafts having cam faced end portions 115 120 125 130

thereon providing latches adapted to be engaged by projecting hooks mounted on said base member, a hand grip provided on said latches and spring means in operative engagement with said shafts whereby to normally maintain said latches in a locked position.

14. The combination with a separable buckle comprising a belt holding base member having a clamping member pivotally mounted thereon and a belt fastening link fitting, said clamping member having means thereon cooperating with means on said base member and with said link fitting for interlocking said link fitting with said base member, of a locking device therefor comprising a pair of independently operated members having spaced shafts in parallel alignment journaled in said clamping member, said shafts having opposed cam faced end portions thereon providing independently operated latches adapted to simultaneously or independently engage projections on said base member for locking said clamping member to said base member.

In testimony whereof I affix my signature.
ALBERT C. FOULK.
